CLAIM

The ornamental design for a coat rack, as shown and described.

DESCRIPTION

FIG. 1 is a perspective view.

FIG. 2 is a front elevation view.

FIG. 3 is a rear elevation view.

FIG. 4 is a right side elevation view.

FIG. 5 is a left side elevation view.

FIG. 6 is a top plan view; and,

FIG. 7 is a bottom plan view.

The broken lines shown at the center of the design indicate indeterminate length and the continuation of the design uniformly along its length.
